UNITED STATES PATENT OFFICE.

MICHAEL J. DE GRAVE, OF CHICAGO, ILLINOIS.

CLAMPING DEVICE.

Application filed February 11, 1922. Serial No. 535,805.

To all whom it may concern:

Be it known that I, MICHAEL J. DE GRAVE, a citizen of the United States, and a resident of the city of Chicago, county of Cook, and 5 State of Illinois, have invented certain new and useful Improvements in a Clamping Device, of which the following is a specification.

My invention relates to clamping devices, 10 and has for its principal object the provision of an improved construction of this character which will be highly efficient in use.

A further object of the invention is the provision of a clamping device especially designed for clamping together stretching members of a curtain stretcher frame and by the application of which will greatly facilitate the mounting together of the various members of the frame and disassembling the 20 same.

Other objects will appear hereinafter.

The invention consists in the combinations and arrangements of parts hereinafter described and claimed.

25 The invention will be best understood by reference to the accompanying drawings forming a part of this specification, and in which,

Fig. 1 is a side elevational view of a 30 clamping device embodying the invention;

Fig. 2 is a sectional detail view, of the same, taken substantially on line 2—2 of Fig. 3, and

Fig. 3 is a plan view, of the same.

35 Referring to the drawings 5 and 6 indicate a pair of curtain stretching members, of any approved type, having curtain pin grooves 7 and arranged substantially at right angles with respect to each other.

40 The member 5, as shown, is arranged and adapted to move longitudinally with respect to the member 6 and is clampingly held in operative engagement with the member 6 by means of a clamp A embodying the invention.

The clamp A comprises an elongated resilient plate 8 bent substantially L shaped, as shown, and fixed to the member 5 by suitable nut receiving bolts 9, said 50 bolts 9 passing through the plate 8 adjacent the end of the longest limb c of the plate 8. The shortest limb d of the plate 8, which is bent in parallel relation with respect to the limb portion c, is arranged and 55 adapted to engage the adjacent side of the stretching member 6, when in position, as

shown. Opposite the end of the limb portion c through which the bolts 9 pass, is a rectangularly shaped slot 10 for the passage of the engaging end e of a lever 11, by 60 which the clamping end of the plate 8 is forced into clamping engagement with the member 6. The engaging end e of the lever 11 is bent, a trifle beyond a right angle with respect to the lever providing a foot 12 65 which, when the lever is moved into clamping position to effect a clamping relation between the members 5 and 6 the foot 12 serves to limit the operative movement of the lever. Carried by the lever 11 and forming a part 70 thereof, are trunnions 13 which engage triangularly shaped recesses 14 formed by flexing outwardly the portions of said limb on the opposite sides of said slot in limb portion c of the plate 8, as shown.

To prevent the engaging end of the lever 11 from wearing or working on the adjacent surface of the member 5, I provide a metallic bearing plate 15 interposed between the limb portions e and the adjacent surface of 80 the member 5. As most curtain stretching members are formed of soft wood such as pine, the metallic bearing plate 15 prevents the engaging end of the lever 11 from digging into the member 5 which in the course 85 of time would render the clamping device useless.

The operation of the clamping device, as will be readily understood by referring to the description herein and the drawings, is 90 of such a simple nature that one is enabled to secure the curtain stretching members together and dismount the same in a short time. The clamping device will also prove to be of great value owing to its simplicity in structure and the firm clamping engagement effected between the adjacent curtain stretching members.

While I have illustrated and described the preferred form of construction for carrying 100 my invention into effect, this is capable of variation and modification without departing from the spirit of the invention. I, therefore, do not wish to be limited to the precise details of the construction set forth, 105 but desire to avail myself of such variations and modifications as come within the scope of the appended claims.

Having described my invention, what I claim as new and desire to secure by Letters 110 Patent is:

1. In a clamping device comprising in

combination with a pair of curtain stretching members arranged substantially at right angles with respect to each other and a clamping plate of an opening formed in the body of said plate, there being outwardly flexed portions of said plate at opposite sides of said opening; and a lever having one end passing through said opening, for engagement with the adjacent stretching member whereby said stretching members are clamped together by movement of the lever in one direction, said lever being trunnions on said lever adapted to engage recesses formed by the flexed portions of said plate.

10. In a clamping device comprising in

combination with an L-shaped clamping plate adapted to embrace adjacent curtain stretching members, and having an opening formed in the body thereof and outwardly flexed portions on opposite sides of said opening, of an operating lever passing through said opening and having trunnions engaging recesses formed by the flexed portions of said plate.

20. In testimony whereof I have signed my name to this specification in the presence of two subscribing witnesses.

25. MICHAEL J. DE GRAVE.
